LOCK

Otto E. Seiffert, Baltimore, Md.

Application June 24, 1940, Serial No. 342,003

17 Claims. (Cl. 70—355)

This invention relates to new and useful improvements in key operated locks.

The invention particularly proposes the construction of a key operated lock which is substantially pick proof, that is, which is much more difficult to pick than present day cylinder locks.

This invention contemplates characterizing the lock by the fact that it includes a plurality of coaxial disc shaped tumblers loosely turnably supported and having central apertures with offset cutouts for a combination key, and also having large peripheral combination cutouts for a master projection of an operator for opening the lock. It is proposed to use a movable operator for opening the lock in conjunction with the said disc shaped tumblers, and it is proposed that the moveable operator have a master projection which normally rests against the edges of the tumblers and in a certain turned neutral position of the tumblers is movable into said peripheral combination cutouts, whereby the tumblers may then be turned to move the operator for opening the lock.

An important advantage inherent in the construction recited above resides in the fact that the tumblers, in order to be placed into their neutral positions in which the lock may be opened must necessarily be moved in a multitude of different directions in the planes of the tumblers. It is not possible to properly set the tumblers merely by moving them in a linear direction. It is necessary that they be turned. This motion is a two direction motion.

Moreover, it is proposed that the disc shaped tumblers be loosely turnably supported. It is also proposed that there be a means which prevents the tumblers from turning unless they are centrally supported. This makes a picking operation quite difficult since it is necessary that the tumblers be truly axially supported, in addition to being turned. If a pick is used which moves any of the tumblers slightly laterally they cannot be turned.

Furthermore, the invention proposes to construct the peripheral combination cutouts on the disc shaped tumblers of a much larger size than the master projection of the operator. Moreover, it is proposed that blockades be arranged to prevent the operator from moving to open the lock unless it is in a neutral position in proper relationship with the peripheral combination cutouts, and yet not touching the edges of the cutouts. Consequently, there are no shoulders against which one may feel the tumblers engage the master projection.

In addition to the important dominating features already pointed out, the invention contemplates numerous minor features. For example, certain specific blockades of the nature previously mentioned are proposed. Moreover it is proposed to loosely turnably mount the disc shaped tumblers in a certain fashion. A novel construction of the operator is also contemplated.

10 The invention also proposes a novel construction of key for operating the combination lock. It is proposed to characterize the key by the fact that it is built up from a plurality of discs mounted on a core and that certain of the discs have small peripheral projections which comprises the combination of the key.

It is proposed to so construct the key and the lock that the entire device may be produced from stampings, and possibly, a forging.

20 The invention also proposes to so arrange the combination lock that it may be applied to a door lock, a safe lock, an automobile lock, a padlock, and other types of locks. When applied to a padlock a certain construction of the operator is proposed which is somewhat different from the construction of the operator of a door or safe lock. The chief difference is that in the door and safe locks an arrangement is provided whereby the lock may easily be opened from the inside.

25 The invention also contemplates a novel arrangement for calculating and constructing the various combinations. It is proposed that the code be in letters, and it is proposed that the combinations be built up with uneven numbers and uneven divisions and fractions of a degree so as to confound pickers.

30 For further comprehension, of the invention, and of the objects and advantages thereof, reference will be had to the following description and accompanying drawings, and to the appended claims in which the various novel features of the invention are more particularly set forth.

35 In the accompanying drawings forming a material part of this disclosure:

Fig. 1 is a side elevational view of a key operated lock constructed in accordance with this invention, illustrated with the front wall plate removed.

40 Fig. 2 is an enlarged vertical sectional view taken on the line 2—2 of Fig. 1.

45 Fig. 3 is a fragmentary horizontal sectional view taken on the line 3—3 of Fig. 1 but illustrated with certain parts removed so as to disclose the details of other of the parts.

Fig. 4 is a perspective view drawn on a reduced scale of one of the spacer springs used in the lock.

Fig. 5 is a perspective view drawn on the same scale as Fig. 2 showing one of the disc shaped tumblers of the lock.

Fig. 6 is a side elevational view of the key of the lock.

Fig. 7 is an end elevational view of Fig. 6 looking from the bottom end.

Fig. 8 is a schematic diagram of one of the disc shaped tumblers of the lock drawn on a reduced scale and showing the code system for the construction of a combination.

Fig. 9 is a fragmentary enlarged detailed view of a portion of Fig. 1 to clearly disclose certain details of the lock.

Fig. 10 is a fragmentary view similar to Fig. 9 but showing the parts in a different position.

Fig. 11 is a view similar to Fig. 10 but showing the parts in different positions.

Fig. 12 is a view similar to Fig. 11 but showing the parts in different positions.

Fig. 13 is a view similar to Fig. 12 but showing the parts in different positions.

Fig. 14 is a vertical sectional view of a padlock constructed according to this invention.

Fig. 15 is a vertical sectional view taken on the line 15—15 of Fig. 14.

Fig. 16 is a vertical sectional view taken on the line 16—16 of Fig. 14.

The key operated lock, in accordance with one form of this invention, includes a body 20 from which a bolt 21 extends. The body 20 may be of any design or construction, but preferably it is formed from stamped sheet metal. It is composed of two parts. There is the main body portion 20a having a plurality of projecting lugs 22, and a front wall plate section 20b formed with openings 23 through which the lugs 22 pass. The lugs are bent down to secure the parts of the body together. The body 20 is provided with flanges 24 by which it may be mounted in the edge portion of a door or other place. One end of the body is open. Through this open end the bolt 21 projects. The bolt 21 has a projecting bevel edge portion 21a and a base arm portion 21b which slidably engages along one side of the body portion 20a.

A plurality of coaxially disc shaped tumblers 25a, 25b, 25c, 25d and 25e are loosely turnably supported within the body 20. More specifically, these tumblers are supported within a substantially cylindrical shaped casing 26 which is mounted in the body 20. The casing 26 is formed from a strip of material bent into cylindrical shape. Prongs 27 project from the edge portions of the casing 26 and are adapted to engage through the side walls of the body 20 to fixedly mount the casing 26 within the body, and furthermore to comprise additional means for holding the front wall plate 20b in position.

A pair of spacer springs 28 is disposed between each adjacent pair of the disc shaped tumblers. These springs 28 are stamped from spring sheet material. Fig. 4 disclosed a detail of one of these springs. Each spring 28 is substantially of triangular shape but having blunt apexes so that they may be stamped out from spring sheet material in close proximity to each other. The springs 28 are of a size so that their blunt apexes substantially engage the inner wall of the casing 26. Two of the blunt apexes of the springs 28 are formed with small projections 29. These projections engage into small recessed

portions 26a formed in the side wall of the casing 26. The recessed portions 26a extend axially of the casing 26. The arrangement is such that the springs 28 may move axially of the casing 26. However, they are restrained from turning. The edge portions 28a of each pair of springs 28 are bent towards each other so that the central portions belly outwards and force the disc shaped tumblers into substantially equally spaced distances from each other, as clearly shown in Fig. 2.

The springs 28 frictionally engage the disc shaped tumblers to hold them against free turning. However the tumblers may be turned 15 against the frictional restraint of the springs 28. A blockade system is provided for making it difficult to turn the tumblers. This blockade system includes a plurality of ratchet notches 30 formed at irregular distances on the peripheries of the disc shaped tumblers and adapted to coact with irregularly spaced ratchet teeth 31 projecting inwards from the wall of the casing 26. The ratchet teeth 31 and ratchet notches 30 prevent the disc shaped tumblers from being 20 freely turned in one direction, particularly if the disc shaped tumblers are not properly centered in the casing 26. If a proper key or other centering means is provided, the disc shaped tumblers may be freely turned in either direction.

30 The disc shaped tumblers 25a, 25b, etc., have central apertures 33 with offset cutouts 34 for engagement by a combination key. The offset cutouts 34 have rounded corners 34a so that a picking tool will readily slip off the offset cutouts 35 if an attempt is made to turn the tumblers. The disc shaped tumblers are also provided with large peripheral combination cutouts 35 for a master projection of an operator for opening the bolt 21 of the lock. These peripheral cutouts 40 35 are arranged at various angular distances with relation to the offset cutouts 34, depending on the combination of the lock. The disc shaped tumblers also are provided with toothed cutouts 36 for a toothed projection from the operator previously mentioned. The disc shaped tumblers are also provided with edge areas 37 immediately adjacent the peripheral cutouts 35 capable of jamming with a certain cam projection on the operator as hereinbefore more fully described.

50 An operator is used in conjunction with the tumblers 25a, 25b, etc. In the particular form of the invention illustrated in Figs. 1-5, the operator comprises a bar 38 which is slidably mounted on the base arm portion 21b of the bolt 21. The operator 38 is urged towards the right by a spring 39 which is mounted in the body 20. The bolt 21 is urged towards the left by a spring 40 also mounted in the body 20. The spring 39 is very weak so as to be incapable of moving the operator 38 against the frictional resistance of the springs 28 as hereinafter more fully explained. The operator 38 has an end portion 38a engageable against the shoulder 21bb of the base arm portion 21b for moving the bolt 21. The casing 26 has a laterally projecting portion 26b engaging against the top portion of the shoulder 21bb to form a guide for the base arm portion 21b when the bolt 21 is extended. When the bolt 21 is retracted the edge portions 60 of the head of the bolt are of a sufficiently large area to slidably support the bolt within the body 20 without lateral shifting. A lug 41 is formed on the inner end of the base arm portion 21b and strikes the lateral projection 26b of the casing 26 to limit extension of the bolt 21.

The operator 38 has a master projection 42 which normally rests against the edges of all of the disc shaped tumblers 25a, 25b, etc., as illustrated in Fig. 9. The base arm portion 21b and the operator 38 are as wide as the interior of the body 20. The master projection 42 also extends completely across the interior width of the body 20. In certain turned positions of the disc shaped tumblers 25a, 25b, etc., the master projection 42 is capable of entering the peripheral combination cutouts 35 as will be herein-after more fully explained. Then the operator 38 is capable of assuming a certain neutral position. When it reaches this position it is possible to turn the disc shaped tumblers 25a, 25b, etc., to open the lock. However, even though the master projection 42 enters all of the peripheral combination cutouts 35 it necessarily does not assume its neutral position. The cutouts 35 are much larger than the size of the master projection 42. For this reason the master projection 42 may be slightly to one side, or slightly to the other side of its true neutral position. When in this position the lock cannot be opened as will be apparent as this specification proceeds.

The master projection 42 is formed with a plurality of catch notches 44 which will be in the path of the edge portions of the peripheral combination cutouts 35 and jam therewith when the tumblers 25a, 25c, etc., are in certain positions slightly off their true neutral positions. One of these off positions is illustrated in Fig. 10. The operator 38 has a cam projection 45 extending its full width except for a cutout 45a at one area through which one of the disc shaped tumblers may engage. This cam projection 45 will be in the path of the edge portions 37 of the tumblers 25a, 25b, etc., and jam therewith when the tumblers are in other positions slightly off of their true neutral positions, and hence the operator 38 will be slightly off of its true neutral position.

The operator 38 is also provided with a toothed projection 47 which extends the entire width of the operator. The toothed projection 47 is to one side of the master projection 42. The cam projection 45 is to the other side of the master projection 42. The toothed projection 47 is adapted to engage into toothed cutouts 36 formed on the peripheries of the tumblers 25a, 25b, etc., when the lock is in its open position. The tooth 47 and toothed cutouts 36 are for the purpose of assisting in moving the operator 38 to its closed position to relock the lock, as will hereinafter be more fully explained.

The lock may be opened from the inside. For this purpose there is a handle 50 which has a stem 51 extending through a slot 52 formed in one wall of the body 20. This stem 52 engages into the base arm portion 21b. The handle 50 may be gripped and pulled towards the right (with specific relation to Fig. 1). This retracts the bolt 21 irrespective of the position of the operator 38.

A certain type of key is necessary to open this key operated lock. The key is illustrated in Figs. 6 and 7. It comprises a handle 54 from which a non-circular core 55 projects. A plurality of discs 56a, 56b, 56c, 56d, etc., are formed with central openings so that the discs fixedly engage on the non-circular core 55, that is, non-rotative. Certain of the discs have radial projections 57 forming the combination of the key. The outer end 55a of the core is riveted to fixedly hold the discs in position. The projections 57

appear only on each second disc. The alternate discs are blanks. The projections 57 preferably are arranged at progressive angular distances from each other, producing a right hand spiral.

5 The projections 57 are adapted to extend into the offset cutouts 34 of the disc shaped tumblers. However, it should be noted that the cutouts 34 are much wider than the widths of the projections 57. The purpose of this is to reduce 10 resistance to the insertion of the key into the lock. Moreover, the larger the offset cutouts 34 are, the more difficult it will be to pick the lock, with picking tools. The key is capable of 15 rotatively supporting the tumblers 25a, 25b, etc., so that the ratchet teeth 31 do not engage with the ratchet notches 30.

Fig. 8 schematically illustrates a system for coding locks in accordance with this invention. One of the disc shaped tumblers is illustrated, 20 specifically, the tumbler 25a. It is proposed that a layout be produced having a plurality of radial lines indicated by the letters a, b, d, etc., as illustrated in Fig. 8. These radial lines are at various irregular angular distances from each other. For example, the angle between the radial lines "u" and "h" may be 35 1/4°. A code of 25 letters for a particular combination may be worked out. It is intended that the code be used to locate the offset cutouts 34 in relation to the 30 large peripheral cutouts 35. In this way tumblers of a particular combination may be produced and a key to fit the particular lock. The dot and dash lines 54' in Fig. 8 schematically indicate the handle of the key which must be located in 35 a predetermined direction. For example, in the vertical, extending upwards.

The operation of the lock and its structural details may be better understood from the following description. Assume the lock to be closed, that is, in the position illustrated in Figs. 1 and 9. In this position the operator 38 is to the left of the tumblers 25a, 25b, etc. The weak spring 39 is pushing the operator 38 towards the right engaging the master projection 42 against the 45 edges of the tumblers 25a, 25b, etc.

The lock may be opened by inserting the key into it. The key is gripped by the handle 54 and the outer extremity of the key is engaged through the outer wall of the body 20. The body 50 has an opening 20c into which the tip of the key may engage. The key is moved inwards until the projection 51 from the outermost disc of the key strikes the outer face of the first tumbler 25a. The key is then turned until the projection 51 reaches the offset cutout 34 of the first tumbler 25a. The projection 57 now passes through the cutout 34. The key may be inserted a small distance further until the outermost projection 57 and the next to the outermost projection 57 of the key engage the outer faces of the first and second tumblers 25a and 25b. The key is now pressed slightly inwards so as to slightly flex the spacer springs 28, and the key is now turned until the two projections 57 pick up the two cutouts 34 of the two tumblers 25a and 25b. Then the key may be inserted still further into the lock. In this way the key is worked into the lock until it is fully in position.

It will be readily understood that if the projections 57 are arranged in a right hand spiral the key may easily be properly positioned into the lock by turning it continuously clockwise as it is being fed into the lock. When the key is completely engaged into the lock, all of the tumblers, 25a, 25b, etc., will be axially supported and

hence the ratchet teeth 31 cannot engage any of the ratchet notches 30. The key may now be turned so that the projections 57 of the key simultaneously engage the leading edges of the offset cutouts 34 and simultaneously turn the tumblers 25a, 25b, etc., to a position in which the handle 54 of the key is directed upwards vertically. In this position of the key and tumblers, the spring 39 is free to move the operator 38 to its neutral position. The spring 39 will now move the operator 38 into this position. The parts are now in the position illustrated in Fig. 12. The key may now be turned for rotating all of the tumblers simultaneously and the tumblers in turn will engage the left side of central projection 42 of the operator 38 which is then moved and indirectly moves the bolt 21.

The projection 42 now moves across the tumblers 25a, 25b, etc., to the right hand sides of the tumblers. The lock may be held in its open position by now disturbing the combination merely by turning the key and tumblers and withdrawing the key. To lock the lock it is necessary that the key be re-engaged into the lock as previously described, and that the tumblers be properly aligned by properly positioning the key, and then the key may be again turned for turning the tumblers and locking the lock.

The pick proof nature of the lock may best be understood by considering the operation of one attempting to pick the lock. The first problem of the picker is to turn the tumblers against the blockades of the ratchet teeth 31 and the ratchet notches 30. To do this each tumbler must be supported by at least two points on diametrically opposite sides of its central opening 33. It must be supported centrally to make turning possible. If the picker is successful in doing this he may turn the tumblers. Assume that the tumblers are turned from the position shown in Fig. 9 to the position shown in Fig. 10. The picker has now succeeded in turning the tumblers 25a, 25b, etc., to positions in which the central projection 42 has entered the peripheral cutouts 35 of the tumblers. However, his troubles are not over yet because it is now necessary that the tumblers be properly positioned to permit the operator 38 to assume its truly neutral position.

In Fig. 10, the operator 38 has not as yet assumed its truly neutral position, because one or more of the tumblers are still holding it off. The spring 39 is so weak that it cannot push the operator 38 against the holding action of the tumblers. Instead, the frictional resistance of the springs 28 hold the tumblers fixedly, and it is necessary for the tumblers to be turned before the operator 38 may move. In Fig. 10 the operator 38 happens to be in position slightly to the left of its true neutral position. If any attempt is now made to turn the tumblers it will be found that one of the edges of the cutouts 35 of the tumblers will engage the catch notches 44 of the central projection 42 and the operator 38 becomes jammed.

Fig. 11 shows another position of the tumblers in which the operator 38 is too far to the right of its true neutral position. In this position the cam projection 45 is engaging one or more of the edge areas 37 of the tumblers and an attempt to turn the tumblers to open the lock will cause the cam projection 45 to become wedged in between the operator 38 and the tumblers, foiling the picker.

Fig. 12 shows the correct neutral position for all of the tumblers and for the operator 38. In

this position one of the tumblers has a projection portion 37a engaging the central projection 42 of the operator 38 holding the operator in its true neutral position. This projection 37a is directly over the cutout 45a (see Fig. 3) of the cam projection 45. The main portions of the cam projection 45 is to the left of the edge portions 37, in Fig. 12 so that the cam projection 45 will not function to jam the operator 38 when an attempt is made to turn the tumblers to open the lock. Moreover, the edges 35b of the peripheral cutouts 35 are in a position to miss the catch notches 44. The edges 35b will strike the left hand side of the master projection 42. Now the tumblers may be turned and the operator 38 will be moved to open the lock.

The key will place the parts in the position shown in Fig. 12 very easily for opening lock. It is merely necessary to insert the key and properly position the key. However, a picker attempting to open the lock will have a tremendous job getting the parts into the position shown in Fig. 12.

In Figs. 14-16 inclusive the combination lock, in accordance with this invention, has been applied to a padlock. The padlock includes a body 60 from which a bolt 61 extends. This bolt has an inner operator end portion 62. A plurality of coaxial disc shaped tumblers 25a, 25b, 25c, 25d and 25e are loosely turnably supported within the body 60. These tumblers have central apertures 33 with offset cutouts 34 for a combination key. These tumblers are also provided with large peripheral combination cutouts 35 for a master projection 42 of the operator 62. The disc shaped tumblers are also provided with toothed cutouts 36 for a tooth projection 47 on the operator 62. The operator 62 is also provided with a cam projection 45 adapted to jam in conjunction with certain edge portions of the disc shaped tumblers.

The movable operator 62 comprises merely the inner end portion of the bolt 61. This inner end portion is forged so as to have a pair of passages 64 in which expansion springs 39 are housed. These expansion springs urge the operator 62 towards its neutral position.

The disc shaped tumblers are separated by pairs of spacer springs 28'. The disc shaped tumblers are loosely turnably supported within the body 60 by the side wall portions of the body and by transverse rods 65 riveted through the front and back walls of the body. These rods 65 also serve to support the spacer springs 28'. The spacer springs 28' are substantially of triangular form and at certain of their apexes are formed with cutouts 66 through which the rods 65 pass. The rods 65 are of ratchet tooth construction to coact with ratchet notches 39 formed on the peripheries of the disc shaped tumblers. The body 60 is also provided with certain ratchet tooth projections 31' which also coact with the ratchet notches 30 to limit turning of the disc shaped tumblers in one direction except when they are axially aligned.

In other respects this form of the invention is similar to the previous form and like parts are identified by like reference numerals. It is believed that the operation is substantially identical to the prior form. The only essential difference resides in the fact that, in Figs. 14-16, the operator 62 is integral with the bolt 61, while in the prior form the operator comprises a part separate of the bolt. For this reason in the prior form of the invention the bolt may be opened

from the inside of the door without disturbing the operator. With the padlock construction this is not possible.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. In a lock, a plurality of coaxial disc shaped tumblers loosely turnably supported and having central apertures with offset large cutouts for a combination key having small projections to engage the ends of said offset cutouts and also having large peripheral combination cutouts for a master projection of an operator for opening said lock, and a movable operator for opening said lock and having a master projection normally resting against the edges of said tumblers and in certain turned neutral positions of said tumblers being movable into said peripheral combination cutouts, whereby the tumblers may then be turned to move said operator for opening said lock.

2. In a lock, a plurality of coaxial disc shaped tumblers loosely turnably supported and having central apertures with offset large cutouts for a combination key having small projections to engage the ends of said offset cutouts and also having large peripheral combination cutouts for a master projection of an operator for opening said lock, a movable operator for opening said lock and having a master projection normally resting against the edges of said tumblers and in certain turned neutral positions of said tumblers being movable into said peripheral combination cutouts, whereby the tumblers may then be turned to move said operator for opening said lock, and means for preventing turning of said disc shaped tumblers in one direction when the tumblers are laterally displaced.

3. In a lock, a plurality of coaxial disc shaped tumblers loosely turnably supported and having central apertures with offset large cutouts for a combination key having small projections to engage the ends of said offset cutouts and also having large peripheral combination cutouts for a master projection of an operator for opening said lock, a movable operator for opening said lock and having a master projection normally resting against the edges of said tumblers and in certain turned neutral positions of said tumblers being movable into said peripheral combination cutouts, whereby the tumblers may then be turned to move said operator for opening said lock, and means for preventing turning of said disc shaped tumblers in one direction when the tumblers are laterally displaced, comprising stationary ratchet teeth engageable with ratchet notches formed in the peripheries of the tumblers.

4. In a lock, a plurality of coaxial disc shaped tumblers loosely turnably supported and having central apertures with offset large cutouts for a combination key having small projections to engage the ends of said offset cutouts and also having large peripheral combination cutouts for a master projection of an operator for opening said lock, and a movable operator for opening said lock and having a master projection normally resting against the edges of said tumblers and in certain turned neutral positions of said

tumblers being movable into said peripheral combination cutouts, whereby the tumblers may then be turned to move said operator for opening said lock, said tumblers being coaxially stacked in a substantially cylindrical casing, and ratchet teeth projecting from said casing and engageable with ratchet notches formed in the peripheries of said tumblers when the tumblers are out of center in the casing.

5. In a lock, a plurality of coaxial disc shaped tumblers loosely turnably supported and having central apertures with offset large cutouts for a combination key having small projections to engage the ends of said offset cutouts and also having large peripheral combination cutouts for a master projection of an operator for opening said lock, and a movable operator for opening said lock and having a master projection normally resting against the edges of said tumblers and in certain turned neutral positions of said tumblers being movable into said peripheral combination cutouts, whereby the tumblers may then be turned to move said operator for opening said lock, said tumblers being coaxially stacked in a substantially cylindrical casing, and ratchet teeth projecting from said casing and engageable with ratchet notches formed in the peripheries of said tumblers when the tumblers are out of center in the casing, and resilient means interposed between adjacent faces of said tumblers to resiliently hold the tumblers in spaced positions.

6. In a lock, a plurality of coaxial disc shaped tumblers loosely turnably supported and having central apertures with offset large cutouts for a combination key having small projections to engage the ends of said offset cutouts and also having large peripheral combination cutouts for a master projection of an operator for opening said lock, and a movable operator for opening said lock and having a master projection normally resting against the edges of said tumblers and in certain turned neutral positions of said tumblers being movable into said peripheral combination cutouts, whereby the tumblers may then be turned to move said operator for opening said lock, said tumblers being coaxially stacked in a substantially cylindrical casing, and ratchet teeth projecting from said casing and engageable with ratchet notches formed in the peripheries of said tumblers when the tumblers are out of center in the casing, and resilient means interposed between adjacent faces of said tumblers to resiliently hold the tumblers in spaced positions, said resilient means comprising pairs of spacer springs.

7. In a lock, a plurality of coaxial disc shaped tumblers loosely turnably supported and having central apertures with offset large cutouts for a combination key having small projections to engage the ends of said offset cutouts and also having large peripheral combination cutouts for a master projection of an operator for opening said lock, and a movable operator for opening said lock and having a master projection normally resting against the edges of said tumblers and in certain turned neutral positions of said tumblers being movable into said peripheral combination cutouts, whereby the tumblers may then be turned to move said operator for opening said lock, said tumblers being coaxially stacked in a substantially cylindrical casing, and ratchet teeth projecting from said casing and engageable with ratchet notches formed in the peripheries of said tumblers when the tumblers

are out of center in the casing, and resilient means interposed between adjacent faces of said tumblers to resiliently hold the tumblers in spaced positions, said resilient means comprising pairs of spacer springs, and means acting between said springs and casing for holding the springs against turning.

8. In a lock, a plurality of coaxial disc shaped tumblers loosely turnably supported and having central apertures with offset large cutouts for a combination key having small projections to engage the ends of said offset cutouts and also having large peripheral combination cutouts for a master projection of an operator for opening said lock, and a movable operator for opening said lock and having a master projection normally resting against the edges of said tumblers and in certain turned neutral positions of said tumblers being movable into said peripheral combination cutouts, whereby the tumblers may then be turned to move said operator for opening said lock, and blockade means associated with said operator and tumblers for preventing turning of the tumblers if the tumblers and operator are slightly out of their true neutral positions.

9. In a lock, a plurality of coaxial disc shaped tumblers loosely turnably supported and having central apertures with offset large cutouts for a combination key having small projections to engage the ends of said offset cutouts and also having large peripheral combination cutouts for a master projection of an operator for opening said lock, and a movable operator for opening said lock and having a master projection normally resting against the edges of said tumblers and in certain turned neutral positions of said tumblers being movable into said peripheral combination cutouts, whereby the tumblers may then be turned to move said operator for opening said lock, and blockade means associated with said operator and tumblers for preventing turning of the tumblers if the tumblers and operator are slightly out of their true neutral positions, said blockades include catch notches formed on said master projection and adapted to engage and jam with one of the sides of said peripheral combination cutouts.

10. In a lock, a plurality of coaxial disc shaped tumblers loosely turnably supported and having central apertures with offset large cutouts for a combination key having small projections to engage the ends of said offset cutouts and also having large peripheral combination cutouts for a master projection of an operator for opening said lock, and a movable operator for opening said lock and having a master projection normally resting against the edges of said tumblers and in certain turned neutral positions of said tumblers being movable into said peripheral combination cutouts, whereby the tumblers may then be turned to move said operator for opening said lock, and blockade means associated with said operator and tumblers for preventing turning of the tumblers if the tumblers and operator are slightly out of their true neutral positions, said blockade means including a cam projection adapted to wedge together the operator and the tumbler discs against motion in the event that relative movement of these parts starts when these parts are out of their true neutral positions.

11. In a lock, a plurality of coaxial disc shaped tumblers loosely turnably supported and having central apertures with offset large cutouts for a combination key having small projections to engage the ends of said offset cutouts and also

having large peripheral combination cutouts for a master projection of an operator for opening said lock, and a movable operator for opening said lock and having a master projection normally resting against the edges of said tumblers and in certain turned neutral positions of said tumblers being movable into said peripheral combination cutouts, whereby the tumblers may then be turned to move said operator for opening said lock, said combination cutouts being worked out from a letter code system in which uneven numbers and divisions in fractions of degrees are used to confuse pickers.

12. In a lock having a body and having a bolt extended from said body, a plurality of coaxial disc shaped tumblers loosely turnably supported within said body and having central apertures with offset cutouts for a combination key and also having large peripheral combination cutouts for a master projection of an operator for opening said bolt and also having tooth cutouts for a tooth projection from said operator and also having edge areas capable of jamming with a cam projection of said operator, a movable operator for opening said bolt and having a master projection normally resting against the edges of said tumblers and in certain turned positions of said tumblers approximating neutral positions of the tumblers being movable into said peripheral combination cutouts to a neutral position, said master projection having catch notches which will be in the path of the edge portions of said peripheral combination cutouts and jam therewith when the tumblers are in certain positions slightly off of their true neutral positions, said operator having a cam projection which will be in the path of said edge areas of the tumblers and jam therewith when the tumblers are in other positions slightly off of their true neutral positions, said operator having a tooth projection engaging in the tooth cutouts of said tumblers in the opened position of said bolt to assist in moving the operator to its closed position to relock the bolt, means for resiliently holding said tumblers in separated positions and also frictionally non-rotative, and weak resilient means for urging said operator to its neutral position and being incapable of moving said tumblers against said frictional holding means.

13. In a lock having a body and having a bolt extended from said body, a plurality of coaxial disc shaped tumblers loosely turnably supported within said body and having central apertures with offset cutouts for a combination key and also having large peripheral combination cutouts for a master projection of an operator for opening said bolt and also having tooth cutouts for a tooth projection from said operator and also having edge areas capable of jamming with a cam projection of said operator, a movable operator for opening said bolt and having a master projection normally resting against the edges of said tumblers and in certain turned positions of said tumblers approximating neutral positions of the tumblers being movable into said peripheral combination cutouts to a neutral position, said master projection have catch notches which will be in the path of the edge portions of said peripheral combination cutouts and jam therewith when the tumblers are in certain positions slightly off of their true neutral positions, said operator having a cam projection which will be in the path of said edge areas of the tumblers and jam therewith when the tumblers are in other positions slightly off of their true neutral

positions, said operator having a tooth projection engaging in the tooth cutouts of said tumblers in the opened position of said bolt to assist in moving the operator to its closed position to relock the bolt, means for resiliently holding said tumblers in separated positions and also frictionally non-rotative, and weak resilient means for urging said operator to its neutral position and being incapable of moving said tumblers against said frictional holding means, said operator and bolt being integral.

14. In a lock having a body and having a bolt extended from said body, a plurality of coaxial disc shaped tumblers loosely turnably supported within said body and having central apertures with offset cutouts for a combination key and also having large peripheral combination cutouts for a master projection of an operator for opening said bolt and also having tooth cutouts for a tooth projection from said operator and also having edge areas capable of jamming with a cam projection of said operator, a movable operator for opening said bolt and having a master projection normally resting against the edges of said tumblers and in certain turned positions of said tumblers approximating neutral positions of the tumblers being movable into said peripheral combination cutouts to a neutral position, said master projection have catch notches which will be in the path of the edge portions of said peripheral combination cutouts and jam therewith when the tumblers are in certain positions slightly off of their true neutral positions, said operator having a cam projection which will be in the path of the edge areas of the tumblers and jam therewith when the tumblers are in other positions slightly off of their true neutral positions, said operator having a tooth projection engaging in the tooth cutouts of said tumblers in the opened position of said bolt to assist in moving the operator to its closed position to relock the bolt, means for resiliently holding said tumblers in separated positions and also frictionally non-rotative, and weak resilient means for urging said operator to its neutral position and being incapable of moving said tumblers against said frictional holding means, said operator being slidably mounted on an inner arm portion of said bolt and cooperative with a shoulder on said arm for moving the bolt to open the lock.

15. In a lock having a body and having a bolt extended from said body, a plurality of coaxial disc shaped tumblers loosely turnably supported within said body and having central apertures with offset cutouts for a combination key and also having large peripheral combination cutouts for a master projection of an operator for opening said bolt and also having tooth cutouts for a tooth projection from said operator and also having edge areas capable of jamming with a cam projection of said operator, a movable operator for opening said bolt and having a master projection normally resting against the edges of said tumblers and in certain turned positions of said tumblers approximating neutral positions of the tumblers being movable into said peripheral combination cutouts to a neutral position, said master projection have catch notches which will be in the path of the edge portions of said peripheral combination cutouts and jam therewith when the tumblers are in certain positions slightly off of their true neutral positions, said operator having a cam projection which will be in the path of the edge areas of the tumblers and jam

therewith when the tumblers are in other positions slightly off of their true neutral positions, said operator having a tooth projection engaging in the tooth cutouts of said tumblers in the opened position of said bolt to assist in moving the operator to its closed position to relock the bolt, means for resiliently holding said tumblers in separated positions and also frictionally non-rotative, and weak resilient means for urging said operator to its neutral position and being incapable of moving said tumblers against said frictional holding means, said tumblers being loosely turnably supported within said body by being disposed within a substantially cylindrical casing, and said means for resiliently holding the tumblers comprising spacer springs within said casing and disposed between adjacent faces of the tumblers.

16. In a lock having a body and having a bolt extended from said body, a plurality of coaxial disc shaped tumblers loosely turnably supported within said body and having central apertures with offset cutouts for a combination key and also having large peripheral combination cutouts for a master projection of an operator for opening said bolt and also having tooth cutouts for a tooth projection from said operator and also having edge areas capable of jamming with a cam projection of said operator, a movable operator for opening said bolt and having a master projection normally resting against the edges of said tumblers and in certain turned positions of said tumblers approximating neutral positions of the tumblers being movable into said peripheral combination cutouts to a neutral position, said master projection have catch notches which will be in the path of the edge portions of said peripheral combination cutouts and jam therewith when the tumblers are in certain positions slightly off of their true neutral positions, said operator having a cam projection which will be in the path of said edge areas of the tumblers and jam therewith when the tumblers are in other positions slightly off of their true neutral positions, said operator having a tooth projection engaging in the tooth cutouts of said tumblers in the opened position of said bolt to assist in moving the operator to its closed position to relock the bolt, means for resiliently holding said tumblers in separated positions and also frictionally non-rotative, and weak resilient means for urging said operator to its neutral position and being incapable of moving said tumblers against said frictional holding means, said tumblers being loosely turnably supported within said body by being disposed within a substantially cylindrical casing, and said means for resiliently holding the tumblers comprising spacer springs within said casing and disposed between adjacent faces of the tumblers, and ratchet teeth projecting from said casing and engageable with ratchet notches formed in the peripheries of said tumblers when said tumblers are slightly off from true axial positions within said casing.

17. In a lock having a body and having a bolt extended from said body, a plurality of coaxial disc shaped tumblers loosely turnably supported within said body and having central apertures with offset cutouts for a combination key and also having large peripheral combination cutouts for a master projection of an operator for opening said bolt and also having tooth cutouts for a tooth projection from said operator and also having edge areas capable of jamming with a cam projection of said operator, a movable operator

for opening said bolt and having a master projection normally resting against the edges of said tumblers and in certain turned positions of said tumblers approximating neutral positions of the tumblers being movable into said peripheral combination cutouts to a neutral position, said master projection have catch notches which will be in the path of the edge portions of said peripheral combination cutouts and jam therewith when the tumblers are in certain positions slightly off of their true neutral positions, said operator having a cam projection which will be in the path of said edge areas of the tumblers and jam therewith when the tumblers are in other positions slightly off of their true neutral positions, said operator having a tooth projection engaging in the tooth cutouts of said tumblers in the opened position of said bolt to assist in moving the operator to its closed position to relock the bolt, means for resiliently holding said tumblers in separated
